UNITED STATES PATENT OFFICE.

CHARLES H. HODGKINS, OF PITTSBURGH, PENNSYLVANIA, ASSIGNOR TO WESTINGHOUSE ELECTRIC & MANUFACTURING COMPANY, A CORPORATION OF PENNSYLVANIA.

ELECTROMAGNET DEVICE.

1,389,140.

Specification of Letters Patent. Patented Aug. 30, 1921.

Application filed November 18, 1916. Serial No. 132,086.

To all whom it may concern:

Be it known that I, CHARLES H. HODGKINS, a subject of the King of Great Britain, and a resident of Pittsburgh, in the county of 5 Allegheny and State of Pennsylvania, have invented a new and useful Improvement in Electromagnet Devices, of which the following is a specification.

My invention relates to electromagnetic 10 devices and particularly to time-element relays.

One object of my invention is to provide means whereby the load-setting of a relay may be varied by properly turning one of 15 the coöperating members of its time-element device.

Another object of my invention is to provide means whereby a relay of the above indicated character shall have a substantially 20 quick action after the lapse of a predetermined interval of time, as determined by the setting of its time-element.

A further object of my invention is to provide a device of the above indicated character that shall be simple to construct and effective in its operation.

In the carrying out of my invention, I provide a relay of the solenoid type having movable and stationary magnetizable core 30 members and a winding. A cylindrical internally screw-threaded member is attached to the under side of the stationary core member and is adapted to receive an externally screw-threaded cup member in which a piston, that is operatively connected to the movable core member of the relay, is disposed. Portions of the interior surface of the cup member are cut away near the top 35 thereof in order that, when the piston has advanced to positions adjacent the cut-away portions, the action of the relay will be relatively quick. The load setting of the relay may be adjusted by turning the cup member with respect to the cylindrical member, 40 thereby moving the same longitudinally to vary the air gap between the magnetizable core members.

In the accompanying drawings, Figure 1 is a side view, partially in section and partially in elevation, of a relay embodying my invention, Fig. 2 is a view taken on the line II--II of Fig. 1, and Fig. 3 is a detail view of a portion of the device shown in Figs. 1 and 2.

The relay 1 comprises, in general, a stationary magnetizable core member 2, a movable magnetizable core member 3, a winding 4 and a time-element and load-adjusting device 5.

The load-adjusting and time-element device 5 comprises a cylindrical internally screw-threaded member 6 that is operatively connected, at one of its ends, to the lower side 7 of the stationary magnetizable core member 2. A substantially cylindrical cup member 8 having an externally screw-threaded flange 9 is adapted to be received by the cylindrical member 6 and is provided with a groove 10, in its outer surface, to receive a holding spring 11 that is secured to the outer 60 surface of the cylindrical member 6. A piston 12 of substantially cup shape is secured to the lower end of the movable core member 3. The piston 12 is provided with a plurality of relatively large openings 13 and a plurality of relatively small openings 14. A washer member 15 is loosely disposed in the piston and is of such shape that it is adapted to normally cover the openings 13 but not the openings 14. A segmental washer 70 member 16 is disposed on the under side of the piston 12 and is adapted to be secured in any desired position by a nut 17. The washer member 16 is adapted to be so turned that any number of the openings 14 may be 75 uncovered to secure any desired coöperation between the members of the dash pot, and, consequently, any time-element in the operation of the relay. At least one of the openings 14 is adapted to be uncovered under all conditions to preclude the danger of the relay 80 not operating under some conditions.

The piston 12 is adapted to slidably engage the interior of the cup 8 in order that an inverse time-element may be obtained 85 in the operation of the relay. The interior surface of the cup 8 is cut away at points 18 near its upper edge in order that, when the piston 12 has advanced to positions adjacent the cut-away portions, the operation of 90 the movable core member 3 will be materially 95 speeded up.

In order to change the load setting of the device 1, the cup 8 is turned, and, in so turning, is moved longitudinally with respect to the member 6 to cause the movable core member 3 to be moved either toward or away 100 from the central portion 19 of the stationary

core member 2. Thus, the load or current traversing the winding 4, at which it is desirable that the movable core member be actuated, may be readily adjusted. That is, 5 the spring 11 may be adapted to coöperate with a scale (not shown) that may be marked on the outer surface of the cup 8 to indicate the load setting of the device. The spring 11 is adapted to be moved out of engagement 10 with the groove 10 when the cup 8 is turned but will maintain the correct load setting of the device against accidental movement of the cup 8 when it is seated in the groove 10.

I do not limit my invention to the particular structure illustrated, as it may be variously modified without departing from the spirit and scope of the invention as set forth in the appended claims.

I claim as my invention:

20 1. A time-element relay comprising movable and stationary magnetizable members, an internally screw-threaded inclosing casing mounted on the stationary magnetizable member, a movable piston connected to the 25 movable magnetizable member and an externally screw-threaded coöperating dash-pot member for the piston adapted to be screwed into and out of the inclosing casing for adjusting the load setting of the relay 30 throughout the length of the dash-pot member.

2. A time-element relay comprising movable and stationary magnetizable members, an internally screw-threaded inclosing casing 35 mounted on the stationary magnetizable member, a movable piston connected to the movable magnetizable member and an externally screw-threaded coöperating dash-pot member for the piston adapted to be 40 screwed into and out of the inclosing casing to permit engagement of the piston with a portion of the dash-pot member throughout its length.

45 3. In a relay, the combination with stationary and movable core members, of a cylindrical internally screw-threaded inclosing casing disposed on the lower side of the

stationary core member, a cup member adapted to be screwed into the cylindrical casing and having portions of its inner surface cut away toward the upper end thereof, and a piston attached to the movable core member and disposed normally in the lower portion of the said cup member whereby turning the cup member adjusts the initial 55 position of the movable core member.

4. In a relay, the combination with stationary and movable core members, of a cylindrical internally screw-threaded casing disposed on the lower side of the stationary 60 core member, a cup adapted to be screwed into the cylindrical casing and having portions of its inner surface cut away toward the upper portion thereof, and a piston attached to the movable core member and so 65 disposed in the said cup that when the cup is turned the position of the movable core member is changed.

5. In a relay, the combination with stationary and movable magnetizable members, 70 of a cylindrical internally screw-threaded inclosing casing disposed on the lower side of the stationary magnetizable member, a cup member adapted to be screwed into the cylindrical casing, and a piston attached to 75 the movable magnetizable member and co-operating with the cup member to permit acceleration of the piston toward the end of its travel.

6. In a relay, the combination with stationary and movable magnetizable members, 80 of a cylindrical inclosing casing disposed on the lower side of the stationary magnetizable member, a cup member adapted to be advanced into the casing, a piston attached 85 to the movable magnetizable member, and means for so supporting the cup member on the cylindrical member as to permit the piston to move throughout the length of the cup member.

In testimony whereof, I have hereunto 90 subscribed my name this 31st day of Oct., 1916.

CHARLES H. HODGKINS.
